(57) **CLAIM**

The ornamental design for a T handle, as shown and described.

DESCRIPTION

FIG. 1 is a front perspective view of a T handle showing my new design;

FIG. 2 is a front elevation view thereof;

FIG. 3 is a rear elevation view thereof;

FIG. 4 is a right side elevational view thereof, the left side is a mirror image;

FIG. 5 is a top plan view thereof; and,

FIG. 6 is bottom plan view thereof.

My T handle is characterized by a tapering outward top face shown in FIG. 1, a curved bottom, and sloping handle grip shown in FIGS. 1, 3, and 5.
